LENS ANTENNA SYSTEM

William Sichak, Lyndhurst, and Edwin P. Westbrook, Nutley, N. J., assignors to International Telephone and Telegraph Corporation, Nutley, N. J., a corporation of Maryland

Application December 10, 1954, Serial No. 474,359

14 Claims. (Cl. 343—783)

This invention relates to directional antenna systems and more particularly to antennas of the lens type and arrays thereof particularly useful in transmission and reception of radio frequency energy in the microwave region.

Efforts have been made heretofore to provide high resolution antenna arrays, such that the beam width is less than about one degree. Such arrays are generally used with a separate reflector to produce the desired vertical pattern, generally cosecant. The advantages of the array-reflector combination over the single fed antenna-reflector combination are that separate control of the azimuth and elevation patterns are possible, the reflector may comprise a simple cylindrically curved member and better control is obtained of polarization. The main disadvantage, however, is the greater complexity of the feeding system for the array.

To obtain a linear array it has been proposed heretofore to employ an end-fed waveguide or coaxial line provided with slots and/or dipoles, or a pill box. In end-fed arrays, the difficulties experienced are shift of beam with frequency, mutual impedance between adjacent slots and the large number of slots required. The pill box or sectoral lens is objectionable because of its large size and weight.

In the copending application of W. Sichak, Serial No. 332,424, filed January 21, 1953, a linear array is disclosed which proved exceptionally well for both transmission and reception compared to prior art arrays for broad band frequency scanning but the feeder arrangement thereof had an overall radiation loss sufficient to produce objectionable side lobes. In one model the array comprised thirty-two radiation elements, each of which was fed through a power divider arrangement from a common feeder. This arrangement required thirty-one separate power dividing junctions. While the loss at each junction was in itself negligible, yet the sum of the losses of all the junctions resulted in sufficient radiation to produce undesirable side lobes.

One of the objects of this invention is to provide such an array with means to eliminate or greatly minimize the aforementioned side lobes; and another object is to provide a new array capable of covering a corresponding frequency band wherein the number of radiation units and power dividing junctions are greatly reduced.

Still another object is to provide a new lens type of antenna having highly directive characteristics; and a further object is to provide an improved linear array employing lens antennas.

One of the features of the invention is a simplified type of lens antenna comprising two spaced parallel planar conductors and a layer of dielectric material filling the space between the conductors, the forward edge of the dielectric layer being arcuately curved in a plane parallel to said planar conductors to focus radio frequency energy propagated therethrough.

Another feature is the arrangement of such lens an-

2

tennas in an array as to provide for the printing of the waveguide feeders for the antenna units of the array.

The array includes a planar conductor which carries a layer of dielectric material, the individual antenna elements each being defined by a tapered conductor section carried on the dielectric layer and the curved forward edge of the dielectric layer adjacent said tapered section. Each tapered section of the array is fed by a conductor strip also carried by the dielectric layer in closely spaced parallel relation to the planar conductor whereby radio frequency energy is guided by the strip in conjunction with the planar surface of the planar conductor. To eliminate or at least minimize radiation from the power dividing junctions feeding the strips, a second planar conductor is disposed in overlying spaced shielding relationship to the antenna sections, the individual feeders and the power dividing junctions coupled thereto. Each lens portion of the antenna array is such as to accomplish the same radiation normally obtained by eight of the antennas in the aforementioned model. By employing lens antennas of the character herein disclosed the number of power dividing junctions is greatly decreased.

The above-mentioned and other features and objects of this invention will become more apparent by reference to the following description taken in conjunction with the accompanying drawings, in which:

Fig. 1 is a view in perspective of an antenna array made in accordance with the principles of this invention;

Figs. 2 and 3 are sectional views taken along lines 2—2 and 3—3 of Fig. 1;

Fig. 4 is a view in plan showing an array of antenna units in which each antenna is provided with a parabolic antenna;

Fig. 5 is a cross-sectional view taken along 5—5 of one of the antenna-parabolic reflector units shown in Fig. 4;

Fig. 6 is a view in perspective of another embodiment of the invention showing an antenna array; and

Fig. 7 is a sectional view taken along line 7—7 of Fig. 6.

Referring to Figs. 1, 2 and 3, a linear array is illustrated employing four lens antennas. The construction of the antennas and the waveguide feeder thereto is based on the "line-above-ground" or "Microstrip" type of waveguide, comprising a first or planar conductor 1 and a second or line conductor 2 spaced apart by a thin strip or layer of dielectric material 3. The two conductors 1 and 2 are preferably of flat strip material, the planar conductor being wider than the line conductor so that propagation of microwave energy therealong is in a mode similar to the TEM mode. While the line conductor may be round or otherwise shaped, it is preferred to provide the line conductor as a ribbon-like strip which is readily formed by known printing processes. The parameters of importance are the width of the line conductor 2 and the thickness of the spacing dielectric 3. The dielectric may be polystyrene, polyethylene, Teflon, fiberglass or laminated fiberglass impregnated with Teflon, quartz or other suitable material of high dielectric quality.

Four antenna units are provided, such as indicated by the tapered conductor sections 4, 5, 6 and 7, and the feeder arrangement therefor comprises three power dividing junctions, as indicated at 8, 9 and 10, fed from a single coaxial input connection. While a coaxial connection is shown coupled to the Microstrip through the planar conductor 1, other known waveguide structures may be substituted. Each antenna unit comprises a tapered conductor section as indicated at 4, the feeder being coupled thereto at the small end of the taper. The lens effect is produced by curving the forward edge of the dielectric layer 3 as indicated at 11. In one full size model built for 9000 megacycles, the width of the lens aperture A

was eight inches while the focal length B was nine inches. The dielectric employed was a Teflon-fiber glass laminate $\frac{1}{8}$ inch thick clad with coupling strips 0.00135" thick. While the tapered sections 4—7 may be terminated at the edge 11 of the dielectric material it need not be so terminated. Where lens antennas are used in an array it is preferable to extend the conductive material of the tapered sections interconnecting such sections in a common sheet 12 and angling the sheet outwardly from the plane of the tapered sections so as to form a horn effect in conjunction with a similarly angled portion 14 formed of the forward extension of the planar conductor 1. Such a horn structure enhances the directiveness of the broadband linear array. A one-surface cylindrical lens 15 may be disposed between the angled portions 13 and 14 with the one-surface face thereof spaced a desired distance from the forward edge of the dielectric 3. The curvature of the lens face may either be concave or convex, the particular curvature being such as to provide the focus effect desired. For design information, reference may be had to pages 388—412 on "Dielectric and Metal-plate Lenses" by J. R. Risser in volume 12 of the Radiation Laboratory Series of 1949.

While the lens antenna array illustrated in Fig. 1 employs only three power dividing junctions and, therefore, minimizes greatly the side lobe effect heretofore experienced with a corresponding 32 antenna array, the radiation pattern may have the side lobe effect entirely eliminated by providing a conductive shield in overlying relationship to the tapered sections and the feeder arrangement therefor. Such a shield is shown by a second planar conductor 16 which is extended rearwardly from the angled section 13 in overlying spaced relation to the tapered section 4—7 and the power dividing junctions 8, 9 and 10. While the dielectric spacing between the conductive strips forming the feeders and tapered sections of the antennas and the planar conductor 1 is in the order of one-eighth inch, the spacing of the shield 16 above the strip material is preferably in the order of one-quarter inch or greater. The provision of this conductive shield over the power dividing junctions of the 32 antenna array was also found to eliminate the undesired side lobes hereinbefore referred to.

In Figs. 4 and 5, an array of single radiator units A to N is disclosed, each unit being built in a manner similar to that described in connection with the antenna units illustrated in Figs. 1, 2, and 3. In Figs. 4 and 5 the single antenna unit comprises a tapered conductive strip 17 disposed in dielectrically spaced relation to a planar conductor 18, a layer of dielectric material 19 filling the space therebetween. The tapered section 17 is fed by a strip 20 one end of which is connected to the small end of the tapered section and the other end of which is terminated in overlying relation to an opening 21 formed in the planar conductor 18. A coaxial waveguide is coupled thereto by the outer conductor 22 being connected to the planar conductor about the opening 21 with the inner conductor 23 extending through the opening for connection to the strip conductor 20. The forward edge of the dielectric material 19 is arcuately shaped as indicated at 24 along with the forward edge of the sector 17. This curved edge of the dielectric material and the conductor 17 provides a lens effect on the radio frequency energy propagated through the dielectric body. Where the antenna is used for transmission the radio frequency energy is fed through the coaxial waveguide to the lens antenna where it is radiated toward a parabolic reflector 25 carried by an extension 26 of the planar conductor 18. By suitably shaping and disposing the reflector 25 radiation in the desired direction is obtained.

In Figs. 6 and 7 a linear array similar to that shown in Fig. 1 is illustrated. The same reference characters are used in this embodiment for corresponding parts illustrated in Fig. 1. One of the distinctions in the embodiment shown in Figs. 6 and 7 is the arrangement of the

shield 16a and the angled wall portion 13a. The conductive strip portion 12 is eliminated so that the tapered conductive sections are terminated at the forward arcuate edges of the dielectric layer 3. The shield 16a may be connected by side supports to the planar conductor 1. Between the angled portion 13a and 14 a lens 27 is arranged in a manner similar to that illustrated for lens 15 in Fig. 1. This lens, however, is of the cylindrical parallel-plate type similar to that described on page 403 of the aforementioned Volume 12 of the Radiation Laboratory Series. It will be understood, of course, that this lens 27 may also be used in the embodiment shown in Figs. 1—3, and if desired, the lens 15 may be used in the embodiment shown in Figs. 6 and 7. It will also be understood by those skilled in the art that a "two-surface lens" may be used if desired in place of the "one-surface lenses" here illustrated.

While we have described above the principles of our invention in connection with specific apparatus, it is to be clearly understood that this description is made only by way of example and not as a limitation to the scope of our invention as set forth in the objects thereof and in the accompanying claims.

We claim:

- 25 1. A lens antenna for radio frequency waves comprising a waveguide having first and second strip conductors and a layer of dielectric material disposing said conductors in parallel spaced relation, said first conductor being wider than said second conductor to present thereto a planar conducting surface for propagation of radio frequency energy therealong in a mode approximating the TEM mode, said second conductor being flared adjacent the end thereof in a plane parallel to said planar surface and said layer of dielectric being terminated adjacent said flared portion with its forward edge arcuately shaped in a plane parallel to said planar surface to produce a focusing effect on radio frequency energy propagated therethrough.
- 30 2. A lens antenna according to claim 1, wherein said first strip conductor extends beyond the forward edge of said layer of dielectric material and is provided with a parabolic reflector disposed at right angles to the plane of said second conductor, the face of said parabolic reflector being disposed toward said layer of dielectric material to reflect radio frequency energy propagated through said layer of dielectric material.
- 35 3. A lens antenna for radio frequency waves comprising a waveguide having first and second strip conductors and a layer of dielectric material disposing said conductors in parallel spaced relation, said first conductor being wider than said second conductor to present thereto a planar conducting surface for propagation of radio frequency energy therealong in a mode approximating the TEM mode, a coaxial line comprising inner and outer
- 40 50 5. conductors, said first conductor having an opening therethrough in underlying relation to said second conductor, means coupling said coaxial line to said waveguide with the outer conductor connected to said first conductor about said opening and the inner conductor extending through said opening and connected to said second conductor, said second conductor being flared adjacent the output end thereof and said layer of dielectric being terminated adjacent said flared portion with its forward edge arcuately shaped in a plane parallel to said planar surface to provide a focusing effect upon radio frequency energy propagated therethrough, said first conductor being extended beyond said layer of dielectric material and provided with a parabolic reflector disposed at right angles to the plane of said surface to reflect wave energy propagated through said layer of dielectric material.
- 55 60 6. A lens antenna for radio frequency waves comprising a waveguide terminated in two spaced parallel planar conductors and a body of dielectric material filling the space between said planar conductors, the forward edge of said dielectric body being arcuately shaped in a plane

parallel to said planar conductors whereby the refraction characteristics of said body provides a focusing effect upon radio frequency waves propagated therethrough, a horn-like portion having two opposed walls angled outwardly with respect to the planes of said planar conductors forward of the forward edge of said body, and a lens disposed between said angled walls with the curved surface of said lens being spaced a predetermined distance forward of said dielectric body.

5. An antenna array for radio frequency waves comprising two spaced parallel planar conductors, a layer of dielectric material filling the space between said planar conductors, one of said conductors having adjacent portions each tapered rearwardly of the forward edge of said dielectric layer to form in conjunction with the other of said planar conductors a plurality of independent waveguide feeders, the forward edge portion of the dielectric layer forward of each tapered section being arcuately curved to focus radio frequency energy propagated therethrough.

6. An antenna array according to claim 5, wherein said plurality of independent waveguide feeders are coupled to a common waveguide feeder for division of wave energy from said common waveguide feeder to said plurality of tapered portions, said waveguide feeders each comprising a conductor strip spaced parallel to the planar conducting surface of said other planar conductor whereby wave energy is propagated between said strip and said planar surface in a mode corresponding approximately to the TEM mode.

7. An antenna array according to claim 6, wherein said planar conductors extend beyond the forward edge of said dielectric layer and at an angle outwardly from the plane of said conductors, said second conductor having a planar extension extending backwardly in spaced overlying shielding relation to said tapered sections and said individual waveguide feeders.

8. An antenna array according to claim 6, further including a third planar conductor disposed in spaced overlying shielding relation to said individual waveguide feeders and the coupling thereof to said common waveguide feeder.

9. An antenna array for radio frequency waves comprising a waveguide terminated in two parallel planar conductors, a layer of dielectric material filling the space between said planar conductors, one of said conductors having adjacent portions tapered rearwardly of the forward edge of said dielectric layer to form in conjunction with the other of said planar conductors a plurality of independent waveguide feeders, the forward edge portion of the dielectric layer forward of each tapered section being arcuately curved to focus radio frequency energy propagated therethrough, and a horn-like portion having two opposed walls of conductive material angled outwardly with respect to the planes of said planar conductors forwardly of the forward edge of said body.

10. An antenna array according to claim 9, wherein said horn-like portion includes a lens disposed between said two walls spaced a given distance forwardly of the

arcuately curved edge portions of said dielectric layer.

11. An antenna array according to claim 9, wherein said plurality of independent waveguide feeders are coupled through coupling connections to a common waveguide feeder for division of wave energy from said common waveguide feeder to said plurality of tapered portions, said waveguide feeders each comprising a conductor strip spaced parallel to the planar conducting surface of said other planar conductor whereby wave energy is propagated between said strip and said planar surface in a mode corresponding approximately to the TEM mode, and a third planar conductor extending rearwardly of one of said walls in spaced overlying shielding relation to said tapered portions, said individual waveguide feeders and the coupling connections between said individual and said common waveguide feeders.

12. An antenna array for radio frequency waves comprising a first planar conductor, a layer of dielectric material overlying said planar conductor, an array of conductor elements carried by said layer, said array of elements lying in a common plane parallel to said first planar conductor and spaced therefrom a small fraction of a quarter wavelength, a conductor strip coupled to each of said elements extending rearwardly in parallel spaced relation to the planar surface of said first conductor to form in conjunction therewith a plurality of independent waveguide feeders, a common waveguide feeder, means coupling said independent waveguide feeders to said common waveguide feeder, and a second planar conductor disposed in overlying shielding relation to and at least a quarter wavelength above said individual waveguide feeders and the coupling connections thereof to said common waveguide feeder.

13. An antenna array according to claim 12, wherein said elements each includes a flat tapered conductive section to which one of said conductor strips is connected and the forward edge of said dielectric layer is arcuately curved adjacent each of said tapered sections to provide a lens effect on the radio frequency energy propagated therethrough.

14. An antenna array according to claim 12 wherein said first and second planar conductors are provided with extensions angled outwardly of the planes thereof and forwardly of said elements, and a lens is disposed between said angled extensions in a given spaced relation with respect to said array of elements.
